UNITED STATES PATENT OFFICE.

HORACE C. GARDNER, OF CHICAGO, ILLINOIS, ASSIGNOR TO HIMSELF AND
GUSTAVUS F. SWIFT, OF SAME PLACE.

LIQUID-COOLER.

SPECIFICATION forming part of Letters Patent No. 484,955, dated October 25, 1892.

Application filed November 20, 1890. Serial No. 372,000. (No model.)

To all whom it may concern:

Be it known that I, HORACE C. GARDNER, a citizen of the United States, residing at Chicago, county of Cook, and State of Illinois, have invented a new and useful Improvement in Apparatus for Cooling Gases, Vapors, and Liquids, of which the following is a full, clear, and exact specification.

This invention has for its object to provide a novel, simple, efficient, and economical apparatus for cooling liquids, gases, vapors, or other fluids by the evaporation of water or moisture upon portions of a coiled pipe exposed to the atmosphere.

15 To accomplish this object, my invention involves the features of construction and the combination or arrangement of devices hereinafter described and claimed, reference being made to the accompanying drawing, in which the figure is a sectional elevation of an apparatus embodying my invention.

In order to enable those skilled in the art to make and use my invention, I will now describe the same in detail, referring to the drawing, wherein—

The letters A indicate two pillow-blocks arranged at a suitable distance apart to receive between them a tank B, which is designed to contain a body of water.

30 The letter A' indicates a spirally-coiled pipe arranged horizontally and having its end portions extended horizontally into journals, which are coincident with the axis of the coiled portion of the pipe and are supported by the pillow-block A in such manner that the coiled pipe can be turned or rotated by suitable means—such, for example, as a pul-

35 ley m, secured to one of the horizontal journals. The coiled portion of the pipe is partially submerged in the water contained in the tank and by rotating the coiled pipe portions thereof are intermittently immersed and then exposed to the atmosphere. The liquid, gas, or vapor to be cooled is caused to flow 40 through the coiled portion of the pipe, and for this purpose one of the journals is provided with an inlet-pipe a, while the other journal is provided with an outlet-pipe b.

45 The pipe A' is coiled in cylindrical form, and 50 by rotating this pipe through the medium of

the pulley m the various parts of the coil are intermittently submerged in the water and then exposed to the atmosphere, whereby the evaporation of the water or moisture upon the portion of the coiled pipe which is exposed to the atmosphere causes the taking up of heat by the water from the hot fluid or vapor in the coiled pipe.

The spiral form of the pipe A' aids materially in forcing liquid therethrough, since the coil extends in such direction as to force the liquid through the pipe as the latter rotates.

In order to carry off the atmosphere laden with the vapor formed by the vaporization of water upon the coiled pipe, I provide an air-delivery pipe e, arranged to deliver air intermittently or continuously longitudinally along the portion of the coiled pipe which is exposed to the atmosphere. The air may be forced through the pipe e in any suitable manner.

By directing the air longitudinally along the spirally-coiled pipe I insure perfect contact of air with the coil and economize in the use of air.

Having thus described my invention, what I claim is—

1. In an apparatus for cooling fluids, the combination, with a tank for containing water, of a pipe coiled into spiral form and arranged horizontally to be partially immersed in the water in the tank, said coiled pipe having its end portions extended into journals, pillow-blocks or supports for the said journals, and means for rotating the coiled pipe, substantially as described.

2. In an apparatus for cooling fluids, the combination of a water-tank, a coiled pipe partially immersed in the water in the tank, pillow-blocks or supports for the end portions of the coiled pipe, means for rotating the coiled pipe, and an air-pipe for delivering air longitudinally along the portion of the coiled pipe which is exposed to the atmosphere, substantially as described.

HORACE C. GARDNER.
